EYEGLASS FRAME

Edward W. Smith, Charleston Heights, S. C., assignor to Alexander Kono, doing business as Kofra, Charleston
Heights, S. C.

Application September 7, 1956, Serial No. 42,872

Term of patent 14 years

(Cl. D57—1)

Fig. 1 is a front perspective view of an eyeglass frame, showing my new design;

Fig. 2 is a front elevational view thereof; and

Fig. 3 is a side elevational view thereof.

The characteristic features of my design for the eyeglass frame disclosed, reside in the temple portions having the configurations shown.

I claim:

The ornamental design for an eyeglass frame, substantially as shown and described.
